US0D1085966S

(12) **United States Design Patent** (10) Patent No.: **US D1,085,966 S**
(45) Date of Patent: ** Jul. 29, 2025

(54) **FENDER TRIM FOR VEHICLES**

(71) Applicant: **Star Sky Motor**, Grand Cayman (KY)

(72) Inventors: **Ying Shan**, Beijing (CN); **Mo Terry Chen**, Beijing (CN)

(73) Assignee: **Star Sky Motor**, Grand Cayman (KY)

(**) Term: **15 Years**

(21) Appl. No.: **35/521,504**

(22) Filed: **May 20, 2024**

(80) **Hague Agreement Data**

Int. Filing Date: **May 20, 2024**

Int. Reg. No.: **DM/238031**

Int. Reg. Date: **May 20, 2024**

Int. Reg. Pub. Date: **Jun. 28, 2024**
